DESIGN FOR A COMBINED DISPLAY CARD AND PENCIL

Henry Hassenfeld, Providence, R. I.

Application April 11, 1938, Serial No. 76,421

Term of patent 7 years

To all whom it may concern:

Be it known that I, Henry Hassenfeld, a citizen of the United States and resident of Providence, in the county of Providence, and State of Rhode Island, have invented a new, original, and ornamental Design for a Combined Display Card and Pencil, of which the following is a specification, reference being had to the accompanying drawing, forming a part thereof.

Fig. 1 is a top plan view of a combined display card and pencil, showing my new design.

Fig. 2 is an edge view of the same, looking in the direction of the arrows of line 2—2 of Fig. 1.

Fig. 3 is an edge view of the same, looking in the direction of the arrows of line 3—3 of Fig. 1.

I claim:

The ornamental design for a combined display card and pencil, as shown.

HENRY HASSENFELD.
